WHEEL GAUGE

Joseph L. Wilson, Matawan, N. J.

Application May 1, 1946, Serial No. 666,370

3 Claims. (Cl. 33—203.15)

1

This invention relates to wheel gauges and it is primarily an object of the invention to provide a device of this kind whereby the camber and caster of wheels may be readily gauged as to angle.

It is also an object of the invention to provide a device of this kind which permits accurate testing of the wheels of a vehicle as to either camber or caster and wherein the device is of a structure to render the same readily portable, thereby materially facilitating its convenience in use.

An additional object of the invention is to provide a device of this kind including an element mounted for adjustment within certain limitations and which serves as an index to denote the starting point of a testing operation and thereby materially simplify the effective use of the device.

The invention consists in the details of construction and in the combination and arrangement of the several parts of my improved wheel gauge whereby certain important advantages are attained, as will be hereinafter more fully set forth.

In order that my invention may be better understood, I will now proceed to describe the same with reference to the accompanying drawings, wherein:

Figure 1 is a view in side elevation of a gauge constructed in accordance with an embodiment of the invention, a second position of the extension rod being indicated by broken lines and an associated wheel being also indicated by broken lines;

Figure 2 is a view in front elevation of the structure as illustrated in Figure 1, with a portion of the base broken away;

Figure 3 is a sectional view taken substantially on the line 3—3 of Figure 1, looking in the direction of the arrows; and

Figure 4 is a sectional view taken substantially on the line 4—4 of Figure 3, looking in the direction of the arrows.

In the embodiment of the invention as illustrated in the accompanying drawings, B denotes a base of desired dimensions and configuration but which has its bottom surface flat and of such dimensions to firmly rest upon a supporting surface, such as a concrete or board floor or other surface, each of which should be smooth and on the horizontal.

Rigidly secured, as at 1, to the base B and preferably at an extremity thereof and at the transverse center of the base B is the lower end

2

of an upright or standard S. This standard S, as herein disclosed, is of channel form with its intermediate or base portion 2 forwardly disposed with respect to the base B. While this upright or standard S may be otherwise constructed, the channel formation has been found to best comply with the requirements of practice as it provides for lightness without sacrificing strength.

10 The upright or standard S is mounted upon the base B in a manner whereby the intermediate or base portion 2 is at right angles to the base B so as to be substantially vertical when the device is in position for use. The portion 2 of the upright or standard S at substantially the longitudinal center is provided with a long slot 3 which extends from substantially one end of the portion 2 to the other. The outer face of the portion 2 to one side of the slot 3 has provided thereon the graduations 4 in inches and which are consecutively numbered from the bottom upwardly, the lowermost number indicating the distance from that graduation to the surface upon which the base B is placed.

15 20 25 Positioned forwardly of the upright or standard S is a flat meter plate P of desired dimensions and which has its opposed flat faces disposed in a direction lengthwise of the upright or standard S and the inner marginal portion of this plate P is defined by a laterally disposed flange 5 which has close contact with the outer face of the portion 2 of the upright or standard S and which flange 5 extends across or bridges the slot 3.

30 35 40 The flange 5 is preferably at right angles to the plate P and is disposed in a direction toward the graduations 4 and the outer margin of this flange 5 is provided with an outstanding index 6 for coaction with the graduations 4 so that the position of the plate P, or more particularly the meter rod 7 bodily movable with said plate, can be readily determined with respect to the surface upon which the device is positioned for a working operation.

45 50 55 Freely insertible through the flange 5 at aligned points spaced lengthwise thereof are the headed members 8 which are also directed through the slot 3. The members 8 are also disposed through a base flange 9 of a guide bracket G and which flange 9 contacts the rear face of the portion 2 of the upright or standard S.

Outwardly of the flange 9, the members 8 have threaded thereon the enlargements 10, herein disclosed as conventional nuts, and interposed between each of the enlargements 10 and the flange

9 of the bracket G is an expansible member 11, herein disclosed as a coil spring of requisite tension encircling the member 8.

The members or springs 11 operate to maintain the flanges 8 and 9 in close frictional contact with the opposed portions 2 of the upright or standard S so that the plate P will be effectively held in selected adjustment along the slot 3 yet be free for ready movement under slight strain or stress along the slot 3 as may be determined by the requirements of practice.

The meter rod 7, hereinbefore referred to, is freely and slidably disposed through the flanges 5 and 9 and through the slot 3 and the forward or front end portion of this rod 7 is provided with an outwardly and laterally disposed pin 12 which is directed through an elongated slot 14 in the tail portion 15 of a swinging index hand or pointer 16 which is herein disclosed as in simulation of an arrow. The pointer or hand 16 is freely mounted for swinging movement upon an outstanding trunnion 17 carried by the plate P and disposed laterally-therebeyond in the same direction as the flange 5.

The top edge 18 of the plate P is curved on a radius concentric with the trunnion 17 and said plate P immediately adjacent to said curved edge 16 is provided with the graduations 19, preferably spaced in sixteenths of an inch. The pointer or hand 16 is preferably at the same side of the plate P as the flange 5 and the trunnion 17 extends beyond the opposite face of the plate P and has freely mounted thereon a rock arm 20.

This arm 20 is of a length to extend beyond the curved edge 18 of the plate P and said extended portion of the arm 20 is returned to provide an inwardly disposed finger 21 which rides along the graduations 19 and constitutes an index for coaction with said graduations. The finger 21 and the adjacent portion of the arm 20 have close frictional contact with the adjacent marginal portion of the plate P to provide means whereby the arm 20 will be effectively held as the same is swung to adjust the finger or index 21 with respect to the graduations 19.

The rod 7 is of such length as may be preferred and is also freely disposed through an outer part 22 of the guide bracket G and which part is spaced outwardly with respect to the flange 9 a distance sufficient to assure rectilinear movement of the rod 7. The part 22, as herein disclosed, comprises a laterally directed flange spaced from and paralleling the flange 9 and which flange 22 extends laterally from an intermediate web 23 disposed along a margin of the flange 9, said web 23 and flanges 9 and 22 being preferably integral.

The rear extremity of the rod 7 has pivotally connected therewith, as at 24, the inner end portion of a rod extension or finger 25. The pivotal connection 24 is such as to allow the extension or finger 25 to have upward swinging movement with respect to the rod 7. When at the limit of its downward movement, the extension rod or finger 25 is in alignment with the rod 7 which is assured by contact of the inner portion of the extension rod or finger 25 with the adjacent end portion of the rod 7 at a point in advance of the pivotal connection 24.

When it is desired to test a wheel of a car for camber, the device is placed near the outer side of the wheel upon a horizontal surface and closely adjacent to the wheel. The plate P is then lowered to bring the outer pointed end of the extension arm or finger 25 into contact with the rim of the wheel at its lowermost point. This

contact is made by moving the rod 7 endwise in a direction toward the wheel being tested which will result in a movement of the index or hand 16 outwardly with respect to the graduations 19 and after which the arm 20 is swung to bring the index or finger to the point of register of the index or hand 16. After this operation, the plate P is then moved upwardly and so adjusted along the slot 3 to permit the outer pointed end of the rod extension or finger 25 to have proper contact with the rim of the wheel at the high point thereof. The camber of the wheel will cause this adjustment or movement of the rod 7 to bring the index or hand 16 to a position inwardly of the previously set arm 20 and the graduations between said previously set arm 20 and the second reading of the index or hand 16 will readily show the camber. If the camber should not be as desired, the mechanic will then readily know what is necessary to be done.

It is to be noted that the pointer or hand 16 in its movement will at no time be obstructed by the index or finger 21 and, therefore, the extent of inner or outer camber can be determined with equal facility.

It is believed to be readily obvious that the device as herein described will be operated in substantially the same manner hereinbefore explained for metering camber, should it be desired to meter the caster.

The rod 7 is herein disclosed as having associated therewith an extension rod or finger 25 so that said extension rod or finger may be readily moved upwardly under such conditions where the hub cap of the wheel being tested may intersect the path of travel of the rod 7 as it is moved up or down which is the case with some of the older models of cars.

Overlying one of the side flanges 26 of the upright or standard S and extending substantially from one end thereof to the other is a plate 27. This plate 27 is held in position by the bolts 28 or the like and surrounding said bolts 28 between the flange 26 and the plate 27 are the washers 29 whereby the plate 27 is spaced as desired from the adjacent flange 26.

The adjacent edge of the plate 27 is straight from end to end and substantially parallel with the front face of the portion 2 of the upright or standard S.

Mounted for free movement along the plate 27 is a slide 30 provided in its forward marginal portion with an index or pointer 31 for coaction with the graduations 4 on the upright or standard S. This slide 30 has threaded therethrough a binding screw 32 coacting with the plate 27 in a manner whereby the slide 30 may be held in desired selected position along the plate 27. This slide 30 provides means for registering such measurements as may be deemed advisable during the use of the device.

It is to be noted that the tail portion 15 of the index or pointer 16 is of a length to extend below the meter plate P and said extended part is provided with an outstanding knob 33 or the like. This arrangement provides for the ready and convenient shifting of the rod 7 with a consequent adjustment, of course, of the index or pointer 16.

From the foregoing description it is thought to be obvious that a wheel gauge constructed in accordance with my invention is particularly well adapted for use by reason of the convenience and facility with which it may be assembled and operated.

I claim:

1. A gauging device for testing the camber and caster of wheels, comprising a standard having a slot extending lengthwise thereof, a meter plate having a part contacting the standard and bridging the slot, a guide bracket at the side of the standard opposite to the meter plate, an elongated member freely disposed through the said part of the meter plate, the slot of the standard and through the bracket, expandible means carried by said elongated member and engaging the bracket for frictionally securing the bracket and said part of the plate to the standard, whereby the plate is frictionally held in selected position along the slot, a pointer pivoted on the meter plate, and a rod supported by the bracket for lengthwise sliding movement perpendicular to the slot and operatively coupled to the pointer for swinging the latter.

2. A device of the character described, comprising a base, a vertical standard rigidly secured to the base and comprising a channel member having a relatively wide central portion and spaced longitudinal side flanges, said central portion having a slot lengthwise of the standard, a scale formed along one side of the slot upon the face of the central portion opposite from the flanges, a meter plate having an angularly turned side flange disposed against said face of the central portion of the standard and carrying a pointer for coaction with said scale, an index hand pivotally mounted upon the meter plate for swinging movement in a vertical plane parallel to the slot, a relatively long bracket having a vertically disposed central portion and spaced parallel end flanges, one of the said end flanges of the bracket being disposed between the flanges of the standard against the side of the standard central portion opposite from the meter plate and in covering relation with the slot, the said one of the bracket flanges and the side flange of the meter plate having aligned apertures, coupling elements between the said one of the

bracket flanges and the meter plate flange and passing through the slot, resilient elements carried by said coupling means and frictionally maintaining the central portion of the standard secured between the bracket flange and meter plate flange, the other flange of the bracket also having an aperture aligned with the first mentioned apertures, and a rod supported in and extending through said aligned apertures for lengthwise movement perpendicular to the standard, said rod being operatively coupled at one end with said index hand.

3. A device of the character stated in claim 2 with a bar secured lengthwise of the outer face of the flange of the standard adjacent to said scale, the bar being in spaced relation with the adjacent flange, a runner slidably mounted on the bar, means for securing the runner in a desired position on the bar, and a pointer carried by the runner and disposed across the said central portion of the channel bar for coaction with said scale.
